UNITED STATES PATENT OFFICE

135,884

DESIGN FOR A COASTER VEHICLE

Findley Williams, Northbrook, Ill., assignor to
W. L. Stensgaard & Associates, Inc., a corporation of Illinois

Application March 27, 1943, Serial No. 109,831

Term of patent 14 years

To all whom it may concern:

Be it known that I, Findley Williams, a citizen of the United States, residing at Northbrook, in the county of Cook and State of Illinois, have invented a new, original, and ornamental Design for a Coaster Vehicle, of which the following is a specification, reference being had to the accompanying drawing, forming part thereof.

Figure 4 is a perspective view of the same vehicle with a movable part in an alternative position; and

I claim:

The ornamental design for a coaster vehicle, as shown.

FINDLEY WILLIAMS,
